CLAIM

The joint connector, as shown and described.

DESCRIPTION

FIG. 1 is a top, front, right side perspective view of a joint connector, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front and right side perspective view thereof, in use and exploded condition.

The broken line portion of the figure drawings is included to show unclaimed subject matter only and forms no part of the claimed design.
